Primary Examiner — Vy Koenig(74) *Attorney, Agent, or Firm* — Manatt, Phelps & Phillips, LLP(57) **CLAIM**

The ornamental design for a case, as shown and described.

DESCRIPTION

FIG. 1 is a top end view of a case.

FIG. 2 is a bottom end view thereof.

FIG. 3 is a left side view thereof.

FIG. 4 is a right side view thereof.

FIG. 5 is a front view thereof.

FIG. 6 is a rear view thereof; and,

FIG. 7 is a rear perspective view thereof.

The broken lines in FIGS. 1-7 having a dash-dash configuration depict environmental subject matter and form no part of the claimed design.
